CLAIM

The ornamental design for ribbon pendant, as shown and described.

DESCRIPTION

FIG. 1 is a front perspective view of a ribbon pendant showing my new design;

FIG. 2 is a front view thereof with the back view being a mirror image thereof;

FIG. 3 is a left side view thereof;

FIG. 4 is a right side view thereof;

FIG. 5 is a top plan view thereof; and,

FIG. 6 is a bottom plan view thereof.

The broken lines are included for the purpose of illustrating portions of the ribbon pendant that form no part of the claimed design.
